RECORD PROJECTOR

Albert H. Reiber, Evanston, Ill., assignor to Teletype Corporation, Chicago, Ill., a corporation of Delaware

Application December 30, 1938, Serial No. 248,558

25 Claims. (Cl. 178—42)

The present invention relates to printing telegraph apparatus and more particularly to a page printing telegraph apparatus suitable for displaying in a single viewing location both currently recorded news items and previously prepared advertising matter alternatively.

The principal object of the present invention is to provide in a printing telegraph apparatus means for selectively controlling the display of news and advertising matter.

A feature of the invention is to provide in telegraph printers having page feeding mechanism for normal line feed operations, a secondary paper feed mechanism adapted to supervene the normal line feed mechanism, and means controlled by spaced marginal openings in the paper strip to limit the movement of said supervening paper feed mechanism.

Specifically, in the remote control of printing telegraph apparatus employed in projection systems, the receiving stations at which the news items are printed are provided with stationery having alternate blank and previously prepared advertising areas. To control from a transmitting station the presentation of news items and advertising matter on the screen, the present invention provides for the use of stationery having perforated or notched edges, wherein the notches in the two edges are staggered, the notches along one edge governing the display of news items, and the notches along the opposite edge controlling the display of advertising matter.

The platen of the printing telegraph apparatus employed with the present invention may be rotated either in the normal manner in response to the operation of the standard line feed mechanism of the apparatus, or by means of an auxiliary feed means, through gears and a belt or chain drive arrangement wherein driving power is obtained from the main power shaft of the printing apparatus. When it is desired to display an advertisement in the printer, the operator presses a key, designated "Advertisement key" on the keyboard, which causes a function lever in the printing apparatus to be selected, which closes a contact momentarily, thereby establishing a series circuit through a control relay and a clutch electromagnet. The relay locks, forms a holding circuit, and as the armature of the magnet is attracted it withdraws the pawl from the clutch ratchet, thus permitting the clutch to rotate freely which, through associated pulleys and belts, causes the platen to rotate correspondingly to feed the stationery continuously until a pair of contacts encounters a notch in the

edge of the stationery, at which time the contacts act to short circuit the relay and the magnet, causing the relay to open the holding circuit and causing the magnet to release the pawl to engage the clutch ratchet, thus arresting the movement of the platen. If it is desired to display news items, the "News key" is depressed by the operator, resulting in the selection of a function lever in the printer and the control thereby of a relay and magnet corresponding to the described response to the "Advertisement key" to effect the feeding of the stationery in like manner, until a notch in the opposite edge of the stationery encounters a pair of contacts, which act to short-circuit the control relay and clutch operating magnet similarly to the manner previously described in connection with the advertising matter.

The above objects and features of the invention will be better understood from the following description taken in conjunction with the accompanying drawings wherein,

Fig. 1 is a plan view of a printing apparatus embodying the paper feeding and display arrangement of the present invention;

Fig. 2 is a cross-sectional view taken substantially along line 2—2 of Fig. 1;

Fig. 3 is a fragmentary sectional plan view of the printer of Figs. 1 and 2;

Fig. 4 is a fragmentary end view of the platen unit to show part of the line feed mechanism and platen shifting mechanism;

Fig. 5 is a diagrammatic view of the electrical control circuit, with a schematic showing of parts of the apparatus used in carrying out the present invention.

In the accompanying drawings, like reference characters indicate similar parts throughout the several views. For a complete understanding of details not disclosed herein, and which form no part of the present invention, reference may be had to U. S. Patent No. 1,904,164, issued April 18, 1933 to S. Morton et al.

Having reference to Figs. 2 and 3, a printing apparatus to which the feeding and display mechanism of the present invention is applied comprises a typing unit (shown generally in section in Fig. 2) which includes a primary selecting mechanism, indicated generally as 11 (Fig. 3), which is of the sword-and-T type disclosed in U. S. Patent No. 1,745,633 (fully disclosed in the first mentioned patent), and a secondary selector or selector vane assembly, indicated generally as 12. The selector vane assembly 12 controls, through a series of bell cranks 13 (comparable to bell 55,

cranks 44 to 48 shown in Fig. 1 of Patent No. 1,904,164), a corresponding series of curved code bars 14 carried in a movable type carriage. As set forth in the first-mentioned patent, this type carriage, indicated generally as 15, is movable longitudinally with respect to a stationary platen indicated generally as 16. The type carriage 15 also carries a ribbon feed mechanism, indicated generally as 17.

10 Referring particularly to Fig. 3, a motor 18 supplies power through its pinion 19 and a gear 20 to a main operating shaft 21 which carries the spacing mechanism, indicated generally as 22, and the selector cam assembly, indicated generally as 23. As is known in this type of device, power is communicated from the motor to an operating cam assembly carried on shaft 21 through a grab clutch, such as 25. Portion 24 of grab clutch 25 is pinned to and constantly rotates with the shaft 21, which has also frictionally connected thereto the spacing mechanism 22 and the selecting cam assembly 23. Portion 24 is cooperatively engageable with the splined portion 26 when throw-out lever 27 is operated in timed relation with the reception of code signals.

Positioned parallel to the main operating shaft 21 is a rock shaft 42 (Fig. 2) on which are carried various mechanisms; for example, printing bail 43 and function lever bail 40. The printing bail 43, which is actuated by a printing spring (not shown) in proper timed relation in the operative cycle, functions to reciprocate a pull bar operating member 44. As more fully described in Patent 1,904,164, the selector magnet 35 11 in response to code signal impulses controls through the selecting cam assembly 23 a series of elements 45 (Fig. 3) articulated to the selector vanes of the selector vane assembly 12. The setting of the selector vanes 12 in accordance with a received code combination of impulses is transferred through the bell cranks 13 to the series of curved code bars 14 to cause an alignment of notches therein. Therefore, when the pull bar bail 44 is operated leftwardly (as viewed 45 in Fig. 2) by the printing bail 43, a pull bar 46 drops into the aligned notches and, by means of its shoulder 49, is picked up by the bail 44 to cause, through the gear and rack articulation between said pull bar 46 and the type bar 50 47 associated therewith, the rotation of said type bar about its pivot 48 to bring the type face thereon into printing relation with the platen 16.

The spacing mechanism 22, which is operated following the printing of a character, controls 55 through gear 28, gear 29, shaft 30, gear 31 (Fig. 2) and spacing rack 32, the movement of the type carriage 15 to form character spaces.

Associated with the selector vane assembly 12 are a series of function levers, indicated generally as 51 (Fig. 3), for performing the various normal functions; for example, line feed, platen shift, platen unshift, as well as the special functions of controlling the display of news items or advertising matter in accordance with 65 the present invention. The function levers 51 are pivotally mounted on a common shaft 52 and are guided in a function lever comb 53. Function levers 51 are normally biased in a counterclockwise direction (as viewed in Fig. 2) by 70 a spring 54 individual to each function lever. Function levers 51 are normally maintained in the position shown in Fig. 2 against the pull of their spring 54 by a rod 55 carried by the bail 40.

The platen 16 is rotatably carried on a shaft 75 56 journaled in the side members 57 and 58

of a platen frame assembly. Integral with the platen 16 is a line feed ratchet 59. The platen side frames 57 and 58 are pivotally mounted to the printer side frames 61 and 62, respectively.

Having reference to Fig. 4, there is shown pivotally mounted on the platen side frame 58 a bell crank lever 63 for controlling the line feed operation. Pivotally connected to the upper extremity of the vertical arm of lever 63 is a 10 line feed pawl 64 which cooperates with the line feed ratchet 59. The horizontal arm of the bell crank 63 is pivotally connected to the upper end of a rod or link 65, the lower end of which (as disclosed in Patent 1,904,164) is operatively 15 related to the line feed function lever of the series of function levers 51. Thus, when the function lever bail 40 is rocked in timed relation with the reception of the line feed code signal, the function lever bail rod 55 is lowered, thus 20 permitting the line feed function lever to register with the vanes 12 under the action of its spring 54 to cause, through the aforementioned operative relation, the downward movement of rod 65.

The downward movement of rod 65 causes the clockwise rotation of bell crank 63 (as viewed in Fig. 4) to actuate the line feed pawl rightwardly to engage a tooth on the ratchet 59 to rotate the platen 16 one step in a line feeding 30 direction. On the upward stroke of the rod 65, the lever 63 is actuated counterclockwise and leftward motion is imparted to the pawl 64 in preparation for a succeeding line feed operation. Moreover, as pointed out in Patent 1,904,164, the 35 movement of pawl 64 may be adjusted to cause the platen 16 to be rotated two angular steps to perform double spacing. It is, of course, understood that, as is usual in page printers pressure rollers 66 are provided to cooperate with the 40 platen 16 to cause the line-by-line motion of the paper 67 which is unwound from a paper supply roll, not shown.

Also, pivotally connected to side frame member 58 of the platen frame assembly (Fig. 4) 45 is the upper end of a rod or link 71, the lower end of which is operatively connected or related to the platen shift and platen unshift function code levers of the series of function levers 51, so that upon the selection of the shift function lever, for example, the rod 71 will be actuated downwardly to move the line of printing on the platen 16 upward into alignment with the upper row of characters on the type bars 47. Conversely, when the unshift function code lever 55 is selected, the rod 71 will be actuated upwardly, to rock the platen frame assembly counterclockwise to bring the line of printing again into alignment with the lower row of characters on the type bars 47.

The paper 67 in passing around the platen 16 is directed in front of a backing plate 72 adapted to be shiftable vertically substantially in the same plane under the control of the platen frame assembly. The paper then passes 65 around a guide roller 73, thence between a guide roller 74 and its associated pressure roller 75, and then through a pair of contact rollers 76 and 77 to a paper take-up mechanism (not shown). There are provided for achieving the 70 object of the present invention, two pairs of contact rollers 76 and 77, one pair comprising a contact bank 78 supported by the side frame 61 and the other pair comprising the contact bank 79 supported by side frame 62. The contact roll- 75

ers 76 and 77 (Fig. 2) cooperate with notches 81-A and 81-N (Fig. 1) cut in the marginal edges of the paper 67 for control of the paper feeding and display mechanisms, as yet to be explained.

A shaft 82 is journaled in the side frame 61 of the typing unit, and, as seen in Fig. 1, carries a pulley 83, which is connected by a belt 85 to a pulley 84, fixed to the main operating shaft 21. The pulley 83 is frictionally related to the shaft 82 by a friction clutch comprising the flanged collar 86, a pair of discs of friction material 87, washer 89, and a compression spring 88 positioned between the washer 89 and a washer 91. The friction clutch just described is adjustable by means of a nut 92. Loosely carried on the shaft 82 is a member 93 of an overrunning or one-way clutch, the outer portion of which comprises a ratchet 94 fixed to said shaft. Ratchet 94 of the one-way clutch drives the portion 93 through the instrumentality of rollers 95. Integral with the portion 93 is a grooved pulley 96 (Fig. 1). The platen assembly side frame 57 is pivoted to the printer side frame 61 by means of a fixed stud shaft 97, Fig. 1 and rotatably mounted on the fixed stud shaft 97 is a member comprising a grooved pulley 98 integral with a gear 99. The grooved pulley 98 is connected to the grooved pulley 96 by means of a belt 101. The gear 99 is meshed with a gear 102 integral with the platen 16. Cooperating with the ratchet 94 is the armature 103 of a slow-to-release magnet 104 carried on a bracket 105 secured to the side frame 61. The armature 103 is normally urged in a clockwise direction into engagement with the ratchet 94 by a spring 106.

The constantly rotating shaft 21 imparts, through the groove pulley 84 and belt 85, constant rotation to the grooved pulley 83, which is permitted to rotate on the shaft 82 through the instrumentality of the friction clutch associated therewith. Under these conditions, and with the magnet 104 de-energized, the pawl or armature 103 holds the ratchet 94 against rotation, the pulley 83 slipping on the shaft 82. Now, when the magnet 104 is energized in a manner which will presently be explained, the armature 103 is attracted and hence is withdrawn from engagement with the ratchet 94, whereupon the friction clutch will be effective to cause the rotation of the grooved pulley 83 to be imparted to the shaft 82 to impart, in turn, rotation to the ratchet 94 of the one-way clutch, which, through the rollers 95 will impart like rotation to the portion 93. The rotation imparted to portion 93 is in turn imparted to the grooved pulley 96 which, through the instrumentality of the belt 101, imparts rotation to pulley 98, and thereby to the gear 99. The counterclockwise rotation imparted to gear 99 imparts clockwise rotation to the gear 102 associated with the platen 16. This rotation is imparted to platen 16 independently of the bell crank 63 and pawl 64, causing the ratchet 59 to rotate only against the action of detent 60, so that the paper 67 is advanced around the platen 16 and over the backing plate 72 under the control of the one-way clutch comprising members 93, 94, and 95. The paper 67 thus is passed around the roller 73 and through the rollers 74 and 75, and also through the contacts 76 and 77 to a paper take-up reel (not shown).

The circuit for the slow-to-release magnet 104

is controlled by contacts 107 and 108, Fig. 5, which are in turn controlled by function levers 109 and 110, Fig. 2, respectively. As viewed in Fig. 2, the function levers 109 and 110 are each provided with rearwardly extending tail portions which 5 cooperate with the contacts 107 and 108.

Having reference to Fig. 5 which is a diagrammatic view of the electrical circuit arrangement for controlling the paper feeding mechanism of the present invention, the paper 67 is shown in 10 plan view and has marginal notches 81-A and 81-N. It is understood that the position of the notch at the contacts 76 and 77 at the lower edge of sheet 67 in Fig. 5 is only a transit position to enable (as will presently be explained) the short 15 circuiting of electromagnets 104 and 121. The normal position of the notch and contacts 76 and 77 is as shown in connection with contact bank 79 in Fig. 1. The same explanation applies to the notch and contacts 76 and 77 associated 20 with contact bank 78. The contacts 107 and 108 are shown diagrammatically as being controlled by the function levers 109 and 110, respectively. For the purposes of the present description, function lever 110 will be considered 25 as the "news" function lever, and the function lever 109 will be considered as the "advertisement" function lever. When it is desired to display or present a news item in a predetermined position in front of the backing plate 72 for projection on the screen, the setting of the vanes 12 in accordance with the code combination allotted to the news displaying function will cause the operation of the function lever 110, which when selected will rotate about the pivot 52 to raise the tail portion upwardly to close the contact 108 which will complete a circuit from positive battery, through contact 108, thence through relay 30 111, and resistor 112, then over conductor 113, 35 through the winding of the slow-to-release magnet 104, then over conductors 114 and 115 and through the resistor 116 to negative battery. The magnet 104 will become energized upon the completion of this circuit which is closed only momentarily, but which becomes locked up over a 40 circuit traced from positive battery through the contact 117 associated with the relay 111 which, as is understood, has also become energized with the magnet 104 causing the contact 117 to become closed. The locking circuit for the magnet 104 then is traced through the relay 111, resistor 112, conductor 113, winding of magnet 104, then over the conductors 114 and 115 and through the resistor 116 to negative battery. 45

Under these conditions the armature 103 has been attracted so as to become disengaged from the ratchet 94, thus permitting the platen 16 to be subjected to the control of the over-running clutch to advance the paper 67 continuously until a notch 81-N has been presented between the pair of contact rollers 77-N and 76-N of the contact bank 79, whereupon the magnet 104 will become short-circuited over the following path: from positive battery, through the contact 117, 55 over the conductor 118, through the contact rollers 76-N and 77-N of the contact bank 79, thence over the conductor 119 and through the resistor 116 to negative battery. This causes the slow-to-release magnet 104 to become de-energized, as well as the locking relay 111. However, due to the delayed release of the slow-to-release magnet 104, the paper 67 continues to move until it assumes the position shown in Fig. 1 with respect to the contacts of contact bank 79, wherein 60 65 70 75

it is shown that the notch 81—N has passed slightly beyond the contact rollers so as to break the short circuit. This is to assure the operation of the paper feeding and display mechanism of the present invention in response to a succeeding news or advertisement signal combination.

When a code combination associated with the "Advertisement key" is received by the typing unit, the selector vanes 12 will be set characteristically to select the function lever 109 which, through its tail portion closes the contact 107 to complete a circuit from positive battery through contact 107, thence through the relay 121, and resistor, then over the conductor 113, through the winding of the slow-to-release magnet 104, over conductors 114 and 115 and through the resistance 116 to negative battery. Upon the completion of the circuit just traced the magnet 104 and the relay 121 will become energized, the energization of relay 121 acting to close its contact 122 to complete a locking circuit for the magnet 104 extending from positive battery through the contact 122, then through the relay 121, over the conductor 113, through the winding of magnet 104, then over conductors 114 and 115 and through the resistance 116 to negative battery. This circuit will continue closed until the paper 67 has been advanced, in a manner previously described, so as to bring the marginal notch 81—A opposite the pair of contacts 76—A and 77—A associated with the contact bank 78. When this occurs, the previously described locking circuit will be short-circuited from positive battery, through contact 122, over conductor 123, through the contact rollers 76—A and 77—A, over conductor 124, then over conductor 115 and through the resistance 116 to negative battery.

It is thus seen that upon the selective operation of the function levers 109 and 110, the paper sheet 67 containing the advertising matter and the news items is advanced under the control of the slow release magnet 104 and the pairs of contacts 76 and 77. During normal line feed operation under the control of line feed bell crank 68, the platen 16 is rotated line-by-line or step-by-step so as to rotate the gear 102 in like manner, imparting rotation to gear 99 and pulley 98. Since counterclockwise motion is thus imparted to pulley 98 under the control of the printer line feed mechanism, and since the ratchet 94 is held against counterclockwise rotation by the armature 103, the portion 93 of the over-running clutch is free to rotate counterclockwise, thus permitting the performance of the normal line feed operation.

Should it be desired to advance the stationery 67 from one advertisement display position to another advertisement display position without pause in an intermediate news display position, operation of the invention is as follows:

By control of "Advertisement key" the stationery 67 has been positioned in a first advertisement display position, not shown, in which a notch 81—A has permitted contact of rollers 77—A and 78—A as shown in Fig. 5 to short-circuit magnet 104 and relay 121, after which the motion of the stationery 67 in direction of the arrow in Fig. 5 has drawn the notch 81—A beyond the rollers 76—A and 77—A as illustrated at notch 81—N in Fig. 1 and the armature of magnet 104 then has moved into retracted position to engage ratchet 94 to stop the stationery. In this condition, the "Advertisement key" is operated again, operating the function

lever 109 and contacts 107 momentarily, thus energizing and operating the relay 121 and the magnet 104, starting the driving action of the stationery 67 to be stopped when another notch 81—A permits contact between the two rollers 76—A and 77—A. Obviously, the notch 81—N Fig. 5 will permit contact between rollers 76—N and 77—N before another notch 81—A can reach the rollers 76—A and 77—A but the notch 81—N does not cause the stationery to stop. With 110 volts of electrical potential, with resistance of 2,000 ohms in resistor 116, with 100 ohms in magnet 104 and with 100 ohms in relay 121 and resistor 125 jointly, the circuit resistance is 2,200 ohms and the current is .050 ampere. When 15 notch 81—N reaches rollers 76—N and 77—N and permits them to make contact, the winding of relay 111 and resistor 112, having 100 ohms jointly, is connected momentarily in shunt of the winding of magnet 104, reducing the resistance 20 of the circuit to 2,150 ohms and increasing the current to .051 ampere approximately which will divide equally between magnet 104 and marginal relay 111 which by reason of its marginal nature does not operate its armature and movement of 25 stationery 67 continues until a notch 81—A becomes effective upon the pair of rollers 76—A and 77—A to stop the stationery 67 in its next advertisement display position.

Although a particular embodiment of the invention has been disclosed herein, it will be understood that the apparatus is capable of many modifications, and it is contemplated that all changes which come within the range and scope of equivalency are intended to be embraced with- 35 in the purview of the appended claims.

What is claimed is:

1. In a recorder utilizing a continuous strip of record material contoured to comprise two signaling edges, feeding means for feeding said strip in continuous movement, remotely controlled means for starting said feeding means into operation, and two substantially similar means alternately controlled by said edges of said strip for stopping said feeding means. 40

2. In a recorder utilizing a continuous strip of record material contoured to comprise two signaling edges, feeding means for feeding said strip in indefinite continuous movement, two substantially similar remotely controlled means 50 for starting said feeding means into operation, means for selecting either of said remotely controlled means for operation, two substantially similar maintenance means, one associated with each of said remotely controlled means, for continuing the operation of said feeding means, and two substantially similar means controlled by said edges of said strip for stopping said feeding means. 55

3. In a recorder utilizing a continuous strip of record material contoured to comprise two signaling edges, feeding means for feeding said strip in indefinite continuous movement, remotely controlled means for starting said feeding means into operation, and means alternately 60 controlled by said edges of said strip for stopping said feeding means.

4. In a recorder utilizing a continuous strip of record material contoured to comprise two signaling edges, feeding means for feeding said strip in indefinite continuous movement, remotely controlled means for starting said feeding means into operation, stopping means controlled by one of said edges for stopping said feeding means, and further stopping means con- 70 trolled by the other edge for stopping said feeding means, and further stopping means con- 75

- trolled by the other of said edges for stopping said feeding means.
5. In a recorder utilizing a continuous strip of record material contoured to comprise two signaling edges, feeding means for feeding said strip in continuous movement, stopping means controlled by one of said edges for stopping said feeding means, further stopping means controlled by the other of said edges for stopping said feeding means, remotely controlled means for starting said feeding means into operation under control of said first-mentioned stopping means, and further remotely controlled means for starting said feeding means into operation under control of said further stopping means.
6. A recorder having a platen, a primary feeding means for feeding a record medium around said platen, a secondary feeding means, selector mechanism, means controlled by said selector mechanism for initiating the operation of said secondary feeding means and causing said secondary feeding means to supervene said primary feeding means, and means controlled by spaced marginal openings in said medium to limit the feeding movements of said recording medium.
7. In a printing telegraph apparatus, a platen, a line feed mechanism for feeding record paper around said platen, further feeding mechanism comprising a friction clutch and a one-way clutch, selector mechanism, means controlled by said selector mechanism for initiating the operation of said further feeding means and causing said further feeding mechanism to supervene said line feed mechanism, and means controlled by spaced marginal openings in the record paper to limit the movement of said paper.
8. In a printing telegraph apparatus, a platen, a line feed mechanism for feeding record paper around said platen, further feeding mechanism comprising a friction clutch and a one-way clutch, selector mechanism, a plurality of function levers selectively controlled by said selector mechanism, switch means controlled by certain of said function levers for initiating the operation of said further feeding means and causing said further feeding mechanism to supervene said line feed mechanism, and means controlled by spaced marginal openings in the record paper to limit the movement of said paper.
9. In a printing telegraph apparatus, a platen, means for feeding record paper around said platen intermittently, means for feeding paper around said platen continuously, selector mechanism, a plurality of function levers selectively controlled by said selector mechanism, switch means controlled by certain of said function levers for initiating the operation of said second recited means and causing said second recited means to supervene said first recited means, and means controlled by spaced marginal conformations in the record paper to limit the movement of said paper.
10. In a printing telegraph apparatus, a platen, means for feeding record paper around said platen intermittently, means for feeding paper around said platen continuously, selector mechanism, a plurality of function levers selectively controlled by said selector mechanism, switch means controlled by certain of said function levers for initiating the operation of said second recited means and causing said second recited means to supervene said first recited means, and further switch means controlled by spaced marginal conformations in the record paper to limit the movement of said paper.
11. In a printing telegraph apparatus, a platen, means for feeding a record strip around said platen intermittently, other means for feeding said strip around said platen continuously, selector mechanism, a plurality of function levers selectively controlled by said selector mechanism, a slow-to-release magnet for controlling the operation of said other means independently of said first recited means, switch means controlled by certain of said function levers for controlling said magnet, and means controlled by spaced marginal conformations in said record strip for rendering said magnet ineffective to control said other means to thereby limit the movement of said record strip.
12. In a printing telegraph apparatus, a platen, means for feeding a record strip around said platen intermittently, other means for feeding said strip around said platen continuously, and an electrical circuit arrangement for controlling the operation of said other means whereby said other means supervenes said first recited means to feed the record strip independently of said first recited means.
13. In a printing telegraph apparatus, a platen, means for feeding a record strip around said platen intermittently, other means for feeding said strip around said platen continuously, and an electrical circuit arrangement for controlling the operation of said other means whereby said other means supervenes said first recited means to feed the record strip independently of said first recited means, and means controlled by spaced marginal conformations in said record strip to limit the movement of said record strip.
14. In a printing telegraph apparatus, a platen, means for feeding a record strip around said platen intermittently, other means for feeding said strip around said platen continuously, and an electrical circuit arrangement for controlling the operation of said other means whereby said other means supervenes said first recited means to feed the record strip independently of said first recited means, and switch means controlled by spaced marginal conformations in said record strip to limit the movement of said record strip.
15. In a printing telegraph apparatus, a platen, means for feeding a record strip around said platen intermittently, other means for feeding said strip around said platen continuously, selector mechanism responsive to received code combinations of signalling impulses, a plurality of function levers selectively controlled by said selector mechanism, and an electrical circuit including means controlled by certain of said function levers for controlling the operation of said other means whereby said other means supervenes said first recited means to feed the record strip independently of said first recited means.
16. In a printing telegraph apparatus, a platen, means for feeding a record strip around said platen intermittently, other means for feeding said strip around said platen continuously, selector mechanism responsive to received code combinations of signalling impulses, a plurality of function levers selectively controlled by said selector mechanism, and an electrical circuit including means controlled by certain of said function levers for controlling the operation of said other means whereby said other means supervenes said first recited means to feed the record strip independently of said first recited means, and means in said circuit controlled by spaced marginal conformations in said record strip to limit the movement of said record strip.

marginal conformations in said record strip to limit the movement of said record strip.

17. In a printing telegraph apparatus, a platen, means for feeding a record strip around said platen intermittently, other means for feeding said strip around said platen continuously, selector mechanism responsive to received code combinations of signaling impulses, a plurality of function levers selectively controlled by said selector mechanism, and an electrical circuit including means controlled by certain of said function levers for controlling the operation of said other means whereby said other means supervenes said first recited means to feed the record strip independently of said first recited means, and means in said circuit controlled by spaced marginal conformations in said record strip for rendering said included means ineffective to control said other means to thereby limit the movement of said record strip.

18. In a printing telegraph apparatus, a platen, means for feeding a record strip around said platen intermittently, other means for feeding said strip around said platen continuously, selector mechanism responsive to received code combinations of signaling impulses, a plurality of function levers selectively controlled by said selector mechanism, and an electrical circuit including means controlled by certain of said function levers for controlling the operation of said other means whereby said other means supervenes said first recited means to feed the record strip independently of said first recited means, and sensing means in said circuit controlled by spaced marginal conformations in said record strip to limit the movement of said record strip.

19. In a printing telegraph apparatus, a platen, means for feeding a record strip around said platen intermittently, other means for feeding said strip around said platen continuously, an electrical circuit for controlling the operation of said other means whereby said other means supervenes said first recited means to feed the record strip independently of said first recited means, and sensing means controlled by spaced marginal conformations in said record strip to limit the movement of said record strip.

20. In a printing telegraph apparatus, a platen, 50 a constantly rotating shaft, means operatively associated with said shaft for feeding a record strip around said platen intermittently, an auxiliary shaft, means operatively related to said constantly rotating shaft for imparting a 55 constant torque to said auxiliary shaft, a one-way clutch carried by said auxiliary shaft operable under certain operating conditions for feeding said record strip around said platen continuously, and an electrical circuit arrangement for 60 controlling the operation of said clutch whereby said clutch supervenes said first recited means to feed said record strip independently of said first recited means.

21. In a printing telegraph apparatus, a platen, a constantly rotating shaft, means operatively associated with said shaft for feeding a record strip around said platen intermittently, an auxiliary shaft, means operatively related to said constantly rotating shaft for imparting a constant torque to said auxiliary shaft, a one-way 65

clutch carried by said auxiliary shaft operable under certain operating conditions for feeding said record strip around said platen continuously, and an electrical circuit arrangement for controlling the operation of said clutch whereby said clutch supervenes said first recited means to feed said record strip independently of said first recited means, and means controlled by spaced marginal conformations in said record strip to limit the movement of said record strip.

22. In a recorder utilizing a continuous strip of record material contoured to comprise two signaling edges, a platen, means for feeding said strip around said platen intermittently, means for feeding said strip around said platen continuously, selector mechanism, a plurality of function levers selectively controlled by said selector mechanism, switch means controlled by certain of said function levers for initiating the operation of said second recited means and causing said second recited means to supervene said first recited means, and further switch means controlled by said edges of said strip to limit the movement of said strip.

23. In a recorder utilizing a continuous strip of record material contoured to comprise two signaling edges, a platen, means for feeding said strip around said platen intermittently, other means for feeding said strip around said platen continuously, signal responsive means, and an electrical circuit arrangement dually controlled by said signal responsive means and said edges of said strip for controlling the operation of said other means whereby said other means supervenes said first recited means to feed said strip independently of said first recited means for a predetermined time.

24. In a recorder utilizing a continuous strip of record material contoured to comprise two signaling edges, a platen, means for feeding said strip around said platen intermittently, other means for feeding said strip around said platen continuously, an electrical circuit for controlling the operation of said other means whereby said other means supervenes said first recited means to feed the record strip independently of said first recited means, and sensing means controlled by said edges of said strip to limit the movement of said strip.

25. In a recorder utilizing a continuous strip of record material contoured to comprise two signaling edges, a platen, a constantly rotating shaft, means operatively associated with said shaft for feeding a record strip around said platen intermittently, an auxiliary shaft, means operatively related to said constantly rotating shaft for imparting a constant torque to said auxiliary shaft, a one-way clutch carried by said auxiliary shaft operable under certain operating conditions for feeding said strip around said platen continuously, signal responsive means, and an electrical circuit arrangement dually controlled by said signal responsive means and said edges of said strip for controlling the operation of said clutch whereby said clutch supervenes said first recited means to feed said strip independently of said first recited means for a predetermined time.
